UNITED STATES PATENT OFFICE.

DARIUS W. BUNKER, OF QUINCY, MASSACHUSETTS, ASSIGNOR TO UNITED SHOE MACHINERY CORPORATION, OF PATERSON, NEW JERSEY, A CORPORATION OF NEW JERSEY.

COMPOSITE HEEL.

Application filed March 12, 1926. Serial No. 94,201.

This invention relates to shoe heels of the so-called composite type, and is herein illustrated as embodied in a heel comprising a base section which, broadly considered, is scoop shaped and a molded top section, for example of rubber, having a rigid, substantially flat nail anchoring insert.

As heretofore manufactured, a heel base of the scoop shaped type has been so molded as to impart to its attaching face a concave shape such as to fit approximately the heel seat of the shoe to which the base was to be attached. The outer face of the base was correspondingly convex, and difficulties arose if it were desired to employ such a base in combination with a molded top section having a flat nail anchoring insert such, for example, as a known type of rubber heel which has a substantially flat insert of plywood at its attaching face. If it were attempted to fit the rubber heel to the base by gouging or scooping out material from its attaching face to form a cup or concavity to accommodate the convex face of the base the strength of the wooden insert would be seriously impaired or destroyed. If it were attempted to fit the heel to the base by adding sufficient rubber to the attaching face of the heel to produce the necessary concavity the edge of the rubber heel would be undesirably thick and the composite heel would be too high; also the added rubber necessary to produce the concavity to match the base convexity would extend inward from the edge across the nailing line and constitute a yielding element between the wooden insert and the base. There would thus be lost one of the conspicuous advantages of the type of rubber heel above referred to, which is that the nail anchoring insert may be nailed down solidly, directly upon the heel base in relation to which it will not thereafter shift, with a resultant loosening of the nails, as does a rubber heel of the washer type, in which there is yielding rubber between the nail anchoring washers and the surface to which the heel is nailed.

It is an object of the present invention to produce an improved composite heel which will combine to a maximum degree the advantages of both the scoop type of base and the flat insert type of rubber heel or top section, and at the same time overcome the above-mentioned difficulties. To this end I have so modified both the base section and the top section that I am enabled to combine them in

a composite heel which may be readily attached to a shoe with the commercial heelng machinery already in use in shoe factories and which, when so attached, is solid and secure and will give excellent service when the shoe is worn. A further object is to produce a new and improved heel base which can be manufactured at low cost.

In the illustrated embodiment of the invention the base section of the heel is composed of lifts built up to form an individual blank of the maximum thickness required and molded to a generally concavo-convex or scoop shape. The attaching face of the blank is concave and its shape is such as to correspond approximately to that of the heel seat of the shoe to which the heel is to be attached. In the molding operation, in which this shape is imparted to the attaching face of the blank, the outer face of the blank becomes correspondingly convex. Sufficient material is removed from the central portion of this convex face, by cutting or otherwise, to thin its central portion and produce a substantially flat area comprising at least a considerable part of the entire area of the face. Preferably, but not necessarily, the flat area is somewhat less than the entire outer face of the base, leaving a molded marginal portion outside of the flat area which is beveled.

In one aspect of the invention, therefore, a novel method of making heel bases is provided, which method comprises building up an individual heel blank to the maximum thickness desired in the finished base, molding such blank to concavo-convex shape, and thinning the central portion of the blank by removing from the convex face thereof sufficient material to produce a substantially flat foundation for a top section having a flat center.

The molded top section of the heel has, at its attaching face, a rigid substantially flat central portion of approximately the same size and shape as the flat area on the base, surrounded by a raised, inclined rim of molded material shaped to fit approximately the beveled margin of the base.

The base and top sections above described are combined either before or at the time of attachment to the shoe, the cooperating flat faces of the base and top section insuring against the top section rocking upon the base, and the molded rim around the margin of the top section facilitating the fitting together of

the two parts, aiding in securing correct register between the two sections, and producing a tight and perfect joint between the top section and the base.

5 It will be found in practice that the amount of material which it is necessary to remove from the convex face of the base is very small, resulting in a waste of material which is practically negligible, and the removal of 10 this material may be cheaply and rapidly accomplished.

A good practical embodiment of the invention is illustrated in the accompanying drawings, in which

15 Fig. 1 is a perspective view of the improved heel base;

Fig. 2 is a view partly in perspective and partly in cross section of a cushion heel top section adapted to be combined with the base;

20 Fig. 3 is a cross sectional view on the line 3-3 of Fig. 1;

Fig. 4 is a cross sectional view of the base and the top section arranged in assembled relation but before the application of the attaching pressure;

25 Fig. 5 is a cross sectional view of the heel seat end of a shoe with the heel attached thereto.

In the drawings, 10 indicates a two-lift 30 heel base having a generally scoop shaped concave attaching face 12 formed to fit approximately the heel seat of a shoe to which the heel is to be attached. While two lifts are shown, it should be understood that it 35 is within the scope of the invention to use either more or less than two lifts, as may be required to produce, in combination with the rubber heel to be used, a composite heel of the height desired.

40 The base 10, as shown, has, on its outer face a substantially flat area 14 comprising a considerable part of the entire area of said face. Surrounding the flat area 14 is a beveled marginal portion 16 which is illustrated 45 as having a curvature approximately the same as that of the corresponding portion of the attaching face 12, although this may be modified within the limits within which it is practicable to produce the face 16 by compression or molding.

50 The improved heel base 10 may be economically produced by assembling and securing together the required number of lifts to produce an individual blank of the maximum thickness desired in the finished base, molding the flat blank thus produced to a substantially rigid concavo convex scoop shape in a heel compressor and then removing from the outer face of the molded blank, by cutting or otherwise, sufficient material to thin the central portion of the blank and produce the substantially flat surface 14. The size 55 of the flat surface 14 will be determined by the degree of convexity of the molded blank 60 and the amount of material removed. In

some cases the flat area may comprise the entire outer face of the base, but usually it will comprise somewhat less than the entire outer face, leaving the beveled marginal portion 16, as shown in the drawings. In Fig. 3 70 the dotted line 18 shows the contour of the molded blank before the material is removed from its outer face to produce the central, flat area. In making the heel base in the manner described there is no necessity for 75 using a rand or for performing any gouging operation upon the attaching face of the blank. The flat area 14 may be produced by a simple cutting operation with a straight knife, and such a blank may be manufactured 80 at a minimum cost for labor and material.

The top section 20 of the heel is shown as having a body portion 22 of rubber or equivalent cushion material and a flat stiffening, nail anchoring insert or core 24 which, in the present instance, is made of non-moldable plywood. The rubber of a heel of this type is deformable to a certain extent without materially affecting the shape of the wooden core, the exposed face of which is substantially flat. The heel section 20 consequently has, at its attaching face, a substantially flat central portion of approximately the same size and shape as the flat area 14 on the base 10. The flat, central portion of the attaching face of the rubber heel is surrounded by a raised, inclined rim 26 of rubber shaped to fit approximately the beveled margin 16 of the base but inclined somewhat more than the beveled margin 16 for the purpose of producing a tight edge joint between the two sections of the heel when they are pressed tightly together. The thin edge of the rim 26 overlaps somewhat the edge of the core but preferably does not extend inward beyond the nailing line. The heel may, therefore, be nailed down solidly with the core in firm contact with the base, and there will be a thin, narrow sealing rim of rubber which will be pressed tightly between the base and the margin of the wooden core 24, as shown in Fig. 5. The marginal portion of the tread face of the heel section 20 is also curved slightly, as indicated at 28, so that the said tread face shall be deformed to flatness when 115 the heel is attached.

120 In Fig. 5, 30 and 32 indicate respectively the outer sole and insole of a shoe to which the composite heel of the present invention is attached by nails 34 driven through both sections of the heel, through both soles of the shoe and having their points clinched in the insole. The heads of the attaching nails 34 are seated on or in the wooden core 24 and usually will be concealed by the rubber of the 125 heel body 22 closing over their heads when the nail drivers are withdrawn.

Under the pressure applied by the heel attaching machine the flat face of the wooden core 24 will be seated firmly upon the flat area 130

14 of the base 10 where it will be held solidly by the attaching nails. The cooperating conformation of the marginal portions of the base and the rubber heel insures a tight edge 5 joint without the use of cement, and accurate placing of the rubber heel upon the base is facilitated by the peculiar contours of their engaging faces.

Having described the invention, what is 10 claimed as new and desired to be secured by Letters Patent is:—

1. A composite heel comprising a base section having a concave attaching face shaped to correspond approximately to the heel seat 15 of a shoe and an outer face the central portion of which is substantially flat and the marginal portion of which is beveled, and a molded top section including a substantially flat insert of non-moldable material at the 20 central portion of the attaching face of said top section and surrounded by a raised, inclined, molded rim, shaped to fit approximately the beveled marginal portion of the base.

2. A composite heel comprising a base section having a concave attaching face shaped to fit the heel seat of a shoe and an outer face the central portion of which is substantially flat and the marginal portion of which is 25 beveled, and a molded top section including a substantially flat nail anchoring insert at the central portion of the attaching face of said top section surrounded by a raised, inclined rim of molded material shaped to fit 30 approximately the beveled marginal portion of the base.

3. A composite heel comprising a scoop-shaped leather base section having an outer face the central portion of which is substantially flat and the marginal portion of which is beveled, combined with a rubber top section having a flat insert of plywood exposed 40 throughout a substantial area at the central

portion of its attaching face and surrounded by a raised, beveled rim of rubber, molded to 45 fit approximately the beveled, marginal portion of the base.

4. A composite heel comprising an unyielding scoop-shaped base section combined with a rubber top section having a rigid nail 50 anchoring insert exposed throughout a substantial area at the central portion of its attaching face and surrounded by a raised rim of rubber, the entire exposed area of said nail anchoring insert being complementary to and 55 contacting with the corresponding area of the outer face of the scoop-shaped base.

5. A heel base, comprising one or more lifts of leather, having a concave attaching face molded to fit the heel seat of a shoe, and an 60 outer face comprising a cut central portion which is substantially flat and a molded marginal portion which is beveled.

6. The method of making heel bases which comprises building up an individual blank to 65 the maximum thickness desired in the finished base, molding said blank to concavo-convex shape, and thinning the central portion of the blank by removing from the convex face thereof sufficient material to produce a substantially flat foundation for a top section 70 having a flat center.

7. The method of making heel bases which comprises building up an individual blank to 75 the maximum thickness desired in the finished base, molding said blank to concavo-convex shape, and thinning the central portion of the blank by removing from the convex face thereof sufficient material to produce a substantially flat surface surrounded by an inclined margin upon which a randed top section will fit.

In testimony whereof I have signed my name to this specification.

DARIUS W. BUNKER.
